(57) **CLAIM**

The ornamental design for a car trash can, as shown and described.

DESCRIPTION

FIG. 1 is a front, left and top perspective view of a car trash can, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of a car trash can with the lid open downwards thereof; and,

FIG. 10 is a perspective view of a car trash can with the lid open upwards thereof.

The broken lines shown in the drawings illustrate portions of the car trash can that form no part of the claimed design.
